UNITED STATES PATENT OFFICE.

LANK HUGHES, OF WASHINGTON, DISTRICT OF COLUMBIA.

WIRE STRETCHER.

Application filed August 7, 1925. Serial No. 48,850.

This invention relates to wire stretchers and more especially to that class of wire stretchers adapted for use in stretching wire netting in making window screens, door screens and the like. It is particularly the object of this invention to provide a tool that will grip and stretch the wire over the frame at one and the same operation. This wire stretcher is so simple in its structure and 10 operation that it can be placed in engagement with the wire over the frame and operated to stretch the wire by the use of one hand. Not only is the gripping and stretching of the wire accomplished by one operation 15 of the hand but the releasing of the wire is performed by a simple reverse movement of the hand.

These and other advantages will appear from the following description taken in connection with the drawing in which,

Figure 1 is a side view of the stretcher applied to a screen and showing the position of parts of the stretcher after the wire has been stretched,

Figure 2 is a top plan view of the stretcher as shown in Figure 1,

Figure 3 is a section on line 3—3 of Figure 1,

Figure 4 is a section on the line 4—4 of Figure 1,

Figure 5 is a section on line 5—5 of Figure 1,

Figure 6 is a section on line 6—6 of Figure 1,

Figure 7 is an enlarged view of the mesh gripping jaws.

Figure 8 is a sectional view showing a modification of the parts shown in Figure 5.

This device is composed of two principal 40 elements A and B which are somewhat shaped like the letter Z and are pivotally connected to each other as indicated by the numeral 8. The element A consists of a handle 1 and an intermediate part 2 and a 45 wire gripping part 3. The element B consists of a handle part 4, an intermediate part 5 to which the handle part 4 is pivoted as is indicated by the numeral 6, and a wire gripping part 7.

The wire gripping parts 3 and 7 are bent 50 out of line with their respective elements and into an alignment with each other so that when they are opened and closed by the operation of the handles, they will move in the same plane. The wire gripping parts are composed of fixed guide members 9 and 10

between which adjustable slide members 11 and 12 move and are held. The guide members 9 and 10 may be gripped against the members 11 and 12 by means of some suitable element, in the present instance screw elements 13. The outer ends of the adjustable members 11 and 12 are bent toward each other and have formed thereon wire gripping jaws provided with some protective material indicated by the numeral 14, such as rubber, leather or the like, for protecting the wire from being damaged while it is being seized by the gripper in the operation of stretching. The parts 1 and 2 of the element A are at right angle to each other while the part 3 is at a right angle to the part 2 and extends in a line substantially parallel to part 1. The intermediate part 5 of the element B forms substantially a right angle with the part 7 and has pivoted thereto at 6 the handle 4 which in normal position extends in a line substantially parallel with handle 1 and the part 7. The parts are in normal position when the jaws come in contact with the wire but are not made to tightly grip the wire and the plunger 15, hereafter described, is in its withdrawn position due to the action of the spring 17. Extending from the handle 4 and at right angle thereto at the pivot point 6 is the segment member 22 having on the outer end thereof teeth 21. Between the intermediate parts 5 and 6 there is a headed plunger 15 which has on one surface thereof teeth 20 meshing with teeth 21 to move the plunger back and forth on the operation of the handle 4. The plunger 15 moves in and is guided by a cavity in one side of the intermediate part 5. This cavity is indicated by the numeral 16 and has an enlargement as indicated in Figure 5 in which is housed a spring 17 which serves to hold the plunger in a withdrawn position.

One end of the spring 17 is held and adjusted by means of the screw 18 while the other end is held in place by a projection on the arm 19 which extends from the plunger 15 and is guided back and forth in the cavity 16 as the plunger moves due to the operation of handles or the action of the spring 17.

Figure 8 shows a modified form of plunger and plunger seat. In this form the plunger is substantially circular in shape having on one end thereof teeth 20'. The part of the plunger having thereon the teeth 20' is larger than the other part of the plunger

and affords a shoulder 23 against which the spring 17' engages. The plunger in this instance is located within or circular orifice in the intermediate part 5 and is held within 5 the orifice by means of the teeth 21 on the segment member and by the hollow screw member 24 through which the plunger moves back and forth as it is operated by the movement of the handles 1 and 4. The tension 10 of the spring which surrounds the middle part of the plunger may be adjusted by turning the hollow screw member 24. The screw member is provided with a slot in its outer end by which it may be engaged with 15 some tool to rotate it.

In using this wire pressure the handles 1 and 4 are forced apart whereby the jaws are opened so they may be slipped over the frame through which wire netting is to be 20 attached. After the device has been brought in the proper position and is in engagement with the wire netting the handles 1 and 4 are brought toward each other thereby firmly gripping the wire and forcing the plunger 25 15 in engagement with the frame. The plunger acting upon the frame tends to move the whole stretcher away from the frame and carry therewith the wire netting gripped between the jaws. When this operation has 30 sufficiently stretched the wire the wire is securely fastened to the frame by any suitable means. The operation of this structure can be effected by the use of one hand leaving the other hand entirely free to fasten the 35 wire to the frame.

Attached to handle 1 is a leaf spring 1', as shown in Figure 1. The outer or free end of this engages a beveled end of the plunger 15. The purpose of this spring 1' is to 40 hold the handles apart and the jaws open so that the device may be readily applied in use. The spring 17 holds the plunger in a withdrawn position and the jaws release from the wire but does not serve to hold the 45 jaws open so the device can be readily applied in use. It is this purpose that the spring 1' accomplishes.

Having thus described my invention, what I wish to protect by Letters Patent is:

50 1. In the stretcher, gripping means, stretching means, and means for simultaneously operating the gripping means and the stretching means, said last named means being connected to the gripping means so that whenever the gripping means is operated the stretching means must also be operated.

55 2. In a stretcher, a gripping means, a stretching means, lever means for simultaneously operating the gripping means and the stretching means, said lever being connected to the gripping means so that when it operates the gripping means the stretching means must also be operated.

60 3. In a stretcher, gripping means, stretching means, lever means for simultaneously

operating the gripping means and the stretching means, said lever being connected to the gripping means so that when it operates the gripping means the stretching means must also be operated, and means operating 70 upon the stretching means to release the gripping means.

4. In a wire stretcher, wire gripping means, plunger means for stretching the wire, and a lever for simultaneously operating 75 the gripping means and the plunger means.

5. In a wire stretcher, wire gripping means, plunger means for stretching the wire, lever means for simultaneously operating the plunger means and the gripping means, and means attached to the lever means for releasing the wire gripping means.

6. In a wire stretcher, wire gripping jaws, a plunger slidably in one of the jaws, a lever pivoted to said jaw and engaging said plunger to simultaneously operate the gripping jaws and the plunger to grip and stretch the wire.

7. In a wire stretcher, wire gripping jaws, a plunger slidably connected with one of the jaws, a lever pivoted to said jaw and engaging said plunger to simultaneously operate the gripping jaws and the plunger to grip and stretch the wire, and means tending to automatically release the wire gripping jaws.

8. In a wire stretcher, wire gripping jaws, a plunger slidably connected with one of the jaws, lever means pivoted to one of the jaws and engaging the plunger to simultaneously operate the gripping jaws and the plunger to grip and stretch the wire, and spring means associated with the gripping jaws to automatically release said jaws.

9. In a wire stretcher, wire gripping jaws, a plunger slidably associated with one of the jaws, a lever pivoted to said jaw and engaging said plunger to operate the gripping jaws of the plunger to grip and stretch the wire and spring means associated with the other gripping jaw to engage the plunger and release the jaws.

10. In a wire stretcher, a wire gripping jaw, a second wire gripping jaw, a plunger slidably associated with the second named jaw, a lever pivoted to the second named jaw and engaging said plunger to operate the second gripping jaw and the plunger to grip and stretch the wire, means associated with the plunger for retracting the plunger against the gripping operation of the lever and means associated with the first named gripping jaw and cooperating with the plunger to release the jaws.

11. In a wire stretcher, a wire gripping jaw, a second wire gripping jaw, a plunger slidably associated with the second named jaw, rack teeth on one side of said plunger, a lever pivoted to said second named jaw,

- teeth on said lever and engaging the teeth on the plunger and means associated with the plunger and the first named jaw to retract the plunger and release the jaws.
- 5 12. In a wire stretcher, a wire gripping means, plunger means for stretching the wire, a lever means for simultaneously operating the gripping means and the plunger means and means associated with the plunger means for retracting the plunger means and releasing the wire gripping means.
- 10 13. In a wire stretcher, a wire gripping jaw, a second wire gripping jaw pivotally connected to said first jaw, jaw operating and wire stretching means associated with said jaws and means associated with said jaws for releasing them and withdrawing the wire stretching means.
- 15 14. In a wire stretcher, a wire gripping jaw, a second wire gripping jaw, a plunger associated with one of said jaws and adapted to stretch the wire, means associated with the jaws and the plunger for operating the jaws and advancing the plunger relative to the jaws to grip and stretch the wire, and means acting upon the plunger to retract said plunger and open the jaws after the wire has been stretched.
- 20 15. In a wire stretcher, a wire gripping jaw, a second wire gripping jaw pivotally associated with the first named jaw, a plunger slidably associated with one of said jaws and adapted to stretch the wire, and means associated with the jaws and plunger for operating the jaws to grip the wire and advance the plunger relative to the jaws to stretch the wire, and spring means engaging the plunger to retract said plunger after the stretching of the wire and release the wire gripping jaws.
- 25 16. In a wire stretcher, a wire gripping jaw, a handle rigidly attached thereto, a second wire gripping jaw pivotally mounted on the first named jaw, a handle pivotally mounted on the second named jaw, a plunger slidably associated with the second named jaw, means associated with the pivoted handle and the plunger whereby the plunger may be advanced relative to the jaws to stretch the wire when the handles are moved to operate the gripping jaws, and means associated with the plunger for retracting the plunger and releasing the jaws from the wire.
- 30 17. In a wire stretcher, a wire gripping jaw, a second wire gripping jaw, a plunger slidably mounted within said second named jaw, a handle pivotally mounted on the second named jaw and operatively associated with said plunger to advance the plunger relative to the jaws when the handle is moved to operate the gripping jaw, and means associated with the plunger for retracting the plunger against the operation of the handle and opening the jaws.

In testimony whereof I affix my signature.

LANK HUGHES.
